UNITED STATES PATENT OFFICE.

JOHN A. HUNTER, OF ORLAND, INDIANA.

BRIDLE.

SPECIFICATION forming part of Letters Patent No. 366,108, dated July 5, 1887.

Application filed March 16, 1887. Serial No. 231,138. (No model.)

To all whom it may concern:

Be it known that I, JOHN A. HUNTER, a citizen of the United States, residing at Orland, in the county of Steuben and State of Indiana, 5 have invented certain new and useful Improvements in Bridles; and I do declare the following to be a full, clear, and exact description of the invention, such as will enable others skilled in the art to which it appertains to 10 make and use the same, reference being had to the accompanying drawings, and to the letters and figures of reference marked thereon, which form a part of this specification.

My invention has relation to improvements 15 in bridles; and the novelty consists in the peculiar combination of devices and novel construction and arrangement of parts, as will be hereinafter fully described, and set forth in the claims.

20 The primary object of my invention is to provide a device of the class above named adapted to be attached to an ordinary head-stall of a bridle, which will serve as an over-check-rein in the management of the horse to 25 prevent it from running away, &c.

I have shown an embodiment of my invention in the accompanying drawings, in which—

Figure 1 is a side elevation of parts of a 30 bridle, showing my improved device attached thereto; and Fig. 2 is a horizontal sectional view on the line $x-x$ of Fig. 1, showing one of the brackets with the guide-roller journaled therein.

Referring by letter to the drawings, in which 35 like letters of reference indicate corresponding parts in both the figures, A designates a bridle of any desired construction, which consists of the crown-piece B and a forehead-strap, B'. The vertical strap D carries the 40 usual blinders, c, and to the crown-piece B and the blinders a connecting-strap, D', is secured. The lower end of the vertical strap is adapted to be connected to an ordinary driving-bit.

45 C designates a suspended carrying plate or strap, which is made of a flat piece of steel curved at its upper end, as at c', and which is secured to the crown-piece B in any suitable manner. This suspending-plate C is extended 50 out for a short distance forward of the crown-piece, and then assumes a vertical position, as at d, so that it will lie upon the face of the

horse, the lower end being continued downwardly for a suitable distance, and terminates at a point within a short distance above the 55 nose of the animal, so that it will lie in a position parallel to the line of the strap D of the bridle.

E is a loop-shaped vertical bracket or stand-ard that is screwed or otherwise secured in a 60 base-plate, a, fastened on the upper side at or near the middle of the crown-piece B, and in this bracket is mounted a frictional guide-roller, a', the trunnions of which are loosely 65 journaled in the bracket, so that the roller will turn freely on its axis.

F F' designate brackets of a pattern similar to the bracket E, but preferably of smaller dimensions, which are secured to the suspending-plate at different points of its length, and 70 carry guide-rollers f f', respectively. The bracket F is attached to the plate C at the angle formed by the bend at c', while the other bracket, F', is connected to the lower extreme 75 end of said plate C, in a manner which I will presently describe. The rear-side of the bracket F' is formed with a shank, f', that is adapted to move in a vertical slot, h, made in the plate C in the lower end thereof, so as to slide vertically therein, the shank of said bracket F' 80 being headed to hold it firmly in place and to prevent lateral movement of the same, the bracket being thus capable of a vertical sliding movement on the lower end of the plate C, for a purpose presently set forth.

85 G is the over check or draw rein, which passes over the roller of the bracket E, down over the rollers f f' of the brackets F F', re-spectively, and the lower end of the overdraw-rein is adapted to be connected to any pre-ferred kind of bit, which is to be inserted in the animal's mouth. The rollers of the brack-ets are journaled therein at points a short dis-tance from the front side thereof, so as to leave intermediate spaces through which the over 90 draw or check rein passes, and is thereby pre-vented from being displaced from the brack-ets.

The operation of my device is obvious. The bridle carrying my improved overcheck 100 is placed on the horse's head in the usual man-ner, and a bit attached to the lower end of the over draw or check rein G is inserted in the mouth of the animal. If the horse becomes

frightened in any manner, and attempts to spring forward to break away, the overcheck or draw rein is pulled by the driver to cause a bit attached thereto to press against the roof of the horse's mouth to quickly control it. By means of the movable adjustable bracket F' the pressure exerted by the bit attached to the overdraw-rein may be regulated to provide either a strong or moderate pull of the latter, and thus govern the headway of the horse.

Slight changes can be made in the construction as to the form and proportion of the various parts of my invention without departing from the spirit or gist thereof.

Having thus fully described my invention, what I claim as new, and desire to secure by Letters Patent of the United States, is—

1. In a bridle, the combination, with the headstall, of the carrying-plate having the brackets, and the rollers journaled in the brackets, and the overcheck-rein passing over the rollers, the lower roller being adjustably secured to the lower end of the plate, whereby

the tension exerted by the checkrein upon the mouth of the animal may be regulated, 25 substantially as and for the purpose set forth.

2. In a bridle, the combination, with a headstall, of a vertically-disposed carrying-plate having the loop-shaped guiding-brackets, one above the other, in which are journaled guiding-rollers, and an overdraw-rein passing through the brackets and over the rollers, as and for the purpose set forth.

3. In a bridle, the combination, with a headstall, of a carrying-plate, the fixed brackets at 35 its upper ends, the vertically-adjustable bracket at the lower end of the plate, and an overdraw-rein passing through the brackets, as and for the purpose set forth.

In testimony whereof I affix my signature in 40 presence of two witnesses.

JOHN A. HUNTER.
